UNITED STATES PATENT OFFICE.

ALBERT MONROE WILSON, OF CHEROKEE, IOWA.

FISH-PLATE.

SPECIFICATION forming part of Letters Patent No. 689,270, dated December 17, 1901.

Application filed June 5, 1901. Serial No. 63,221. (No model.)

To all whom it may concern:

Be it known that I, ALBERT MONROE WILSON, a citizen of the United States, and a resident of Cherokee, in the county of Cherokee 5 and State of Iowa, have invented a new and Improved Fish-Plate, of which the following is a full, clear, and exact description.

This invention relates to improvements in fish-plates for railway-rails; and the object 10 is to provide in connection with a fish-plate a simple device operating to hold the plate firmly and permanently in place.

I will describe a fish-plate embodying my invention and then point out the novel features in the appended claims.

Reference is to be had to the accompanying drawings, forming a part of this specification, in which similar characters of reference indicate corresponding parts in both figures.

20 Figure 1 is a perspective view of rail-sections and fish-plates, showing my invention as applied thereto; and Fig. 2 is a sectional elevation thereof.

Referring to the drawings, 1 2 indicate the 25 two meeting ends of railway-rails, which are connected together by the usual fish-plates 3. The lower outwardly-disposed flanges 4 of the fish-plates are provided with tapped openings for receiving set-screws 5. I have here shown 30 two set-screws connected with the flange 4 of a fish-plate; but it is to be understood that a greater number may be employed, if desired. The tie-bolts 6 pass through openings in the fish-plates and through the webs of the rails 35 in the usual manner.

In operation after placing the fish-plates and fastening the nuts on the bolts 6 the fish-plates may be more firmly secured or crowded against the under side of the head of the rail 40 by manipulating the set-screws 5 by means of a wrench or other suitable tool engaging with the angular upper end of the set-screws. The lower ends of these screws of course engage upon the base-flanges of the rail. By 45 tightening these set-screws the fish-plates will

not only be forced tightly against the rails, as before mentioned, but they exert a considerable pressure upon the fastening or tie bolts 6, thus preventing the tie-bolts from becoming loose, as often happens through the constant pounding of trains passing over the rails. 50

My invention may be employed in connection with most of the fish-plates commonly in use. Therefore the only expense attached 55 will be the providing of the set-screws and punching and tapping the holes in the flanges of the fish-plates.

It will be understood that the rocking or clamping movement of the fish-plates is due 60 to the ends of the set-bolts resting merely on the uppersurfaces of the rail-base. Said rocking motion could not occur where the set bolts or screws extended into tapped holes in the rail-base. 65

Having thus described my invention, I claim as new and desire to secure by Letters Patent—

1. A fish-plate, having an outwardly-extended flange at its lower edge, provided with 70 tapped openings, and set-screws for engaging in said openings, the ends of said set-screws being designed to engage on the top of the base-flanges of a railway-rail, substantially as specified. 75

2. A fish-plate, having an outwardly-extended flange at its lower edge and having openings for the passage of tie-bolts, and means carried by said flange for causing a rocking movement of the fish-plate against a 80 railway-rail ahead and also causing it to pinch or bind upon the tie-bolts, substantially as specified.

In testimony whereof I have signed my name to this specification in the presence of 85 two subscribing witnesses.

ALBERT MONROE WILSON.
